ANTENNA SYSTEM

Andrew Alford, New York, N. Y., assignor, by
mesne assignments, to Federal Telephone and
Radio Corporation, a corporation of Delaware

Original application April 26, 1939, Serial No.
270,173, now Patent No. 2,283,897, dated May
26, 1942. Divided and this application July 22,
1941, Serial No. 403,519

9 Claims. (Cl. 250—11)

This is a division of application Serial No. 270,173, filed April 26, 1939, Patent No. 2,283,897, dated May 26, 1942, entitled "Antenna systems."

My invention relates to antenna systems particularly for use with plane polarized waves.

There appears to be considerable evidence favoring the use of directional and guiding systems using horizontally polarized waves for guiding aircraft in the horizontal plane.

A number of different kinds of radiators have been tried experimentally but it has been demonstrated that none of these radiators operates to radiate exclusively horizontally polarized waves. In order that this point may be made more clear, reference is made hereinafter to experiments which have been conducted with course beacon antenna systems. For this experiment the radiator consisted of two horizontal half-wave dipoles crossed, that is, arranged at right angles to each other.

Since the electric field around any linear radiator always points toward the radiator, it is clear that at any point lying above the plane of the two crossed half-wave radiators used, the electric fields at a point above the radiator and a distance away therefrom in a horizontal direction, due to the individual radiators, are not horizontal but are inclined to the horizontal by an amount dependent upon the elevation of the point above the radiator and horizontal distance that it is spaced therefrom. For this reason if a pick-up antenna carried on an airplane be inclined at some angle to the horizontal in a direction transverse to the course of the airplane, the ratio of signals from the two crossed radiators will be changed and the course or apparent plane of equality will shift. These effects of shifting the course due to imperfections in the horizontal radiation were observed during the experiments above mentioned. This effect is of considerable magnitude when the airplane is located at a large vertical angle with respect to the radiator.

When vertically polarized radiators are used this effect is not observed because with the vertically polarized radiators the field is vertical at all points, so that any deformation of the receiving antenna on the airplane will only decrease the magnitude of the received signal but will not decrease the signal from one radiator with respect to the other so as to produce a false or shifted course.

This problem is probably more serious than is at present appreciated because of the possibility that the airplane receiving antenna may be injured during take-off or by sleet, or may simply

be out of proper adjustment and thus produce entirely erroneous indications because of the presence of the vertical as well as the horizontally polarized components of the waves.

There is also another possibility which, so far as I am aware, has not at all been appreciated, namely, that parts of the airplane will pick up the vertically polarized waves and then re-radiate them to the supposedly horizontally polarized receiving antenna. Since each airplane itself may be different in structure, these errors will be inherent in each type of airplane and will be different for each different airplane. This error will also be different for different vertical angles and therefore is not subject to simple compensation. Since such errors will cause different course indications for different airplanes in the field of the same beacon, it is quite obvious that the situation would be intolerable because it would necessitate the individual investigations of each airplane.

All of these different difficulties, as well as some others not specifically enumerated would be eliminated if the electric field of the beacon or localizer antenna giving the course indication were made horizontal at all points. This may be accomplished by an antenna system constructed in accordance with my invention, for producing only plane polarized waves. Such an antenna system for producing only plane polarized waves is likewise readily applicable for stationary receiving systems and will result in a receiving arrangement superior to those now in use since it will be more completely selective to reception of plane polarized waves.

According to my invention I have devised an antenna system which substantially eliminates all of the vertically polarized wave components of a received or transmitted wave. This is accomplished by dimensioning the antenna and so energizing it that the vertically polarized components of a wave will be substantially neutralized in every direction from the antenna.

The provision of such a plane polarizing antenna is one of the principal objects of my invention.

A further object of my invention is to provide a radiating or receiving antenna which will have a radiant action substantially only for plane polarized waves forming substantially a circular radiation pattern in the plane of polarization.

It is a still further object of my invention to provide a receiving system for plane polarized waves utilizing a receiving antenna subject to

reception of only waves polarized in the plane of the antenna.

It is a still further object of my invention to provide a radio beacon built up of antenna units radiating only horizontally polarized waves.

Other objects and advantages of my invention will be apparent from the particular description thereof made in connection with the accompanying drawings illustrating a few of the embodiments of my invention, in which

Fig. 1 illustrates in plan view one form of an antenna constituting an embodiment in accordance with the principles of my invention;

Fig. 2 illustrates in plan view one form of constructive arrangement of the antenna of Fig. 1;

Fig. 18 shows the field pattern from the beacon of Fig. 17; and

Figs. 19 and 20 show views of an antenna structure particularly suited for beacon use.

Turning first to Fig. 1, I have shown an arrangement utilizing an antenna indicated generally at 40 coupled to a high frequency source or load 41.

In Fig. 1, an embodiment of an antenna in accordance with my invention is disclosed. In this figure the antenna 40 is shown coupled to a high frequency source or load 41. The antenna is composed of two conductors comprising sections 42, 43, 44, 45, 46 and 42', 43', 44', 45' and 46', respectively. The conductors are open circuited and are made electrically a half-wave long so

that at the ends of the system will occur current nodes.

Parts of each conductor, namely, 42, 46, and 42', 46' are arranged close to each other and at the ends of conductors 42, 42' is coupled a high frequency translator which may constitute a source of energy or a load. Sections 42, 42' and 46, 46' are preferably chosen of such length that the current maximum occurs at the center of the radiating portion of the conductors, namely, at the mid-point of conductors 44, 44', and the radiating sections comprising portions of the conductors 43, 44, 45 and 43', 44', 45', are made short relative to the operating wavelength so that a substantially uniform current distribution is obtained. These radiating sections are made preferably of a length in the order of $\frac{1}{16}$ to $\frac{1}{8}$ of a wavelength, but should in any case not exceed $\frac{1}{8}$ of a wavelength, while the total overall length of each conductor is preferably $\frac{1}{2}$ a wavelength electrically.

The energy source 41 should be connected to energize the conductors in phase opposition so that the instantaneous direction of current flow is around the periphery in the same direction in the radiant acting elements, and is opposite in the closely spaced conductors. In case 41 is a receiver the receiver is coupled at the same point as would be required for an energy source, in order to obtain the same operation. It is well known that in any antenna system a receiver must be coupled at a point such that if it were replaced by a source the desired characteristics would be obtained. For this reason the connection of the translating device is made in terms of the effect of a source at this point because no other simple generic language is available.

In the illustration of Fig. 1, the two radiant acting portions are shown each substantially $\frac{1}{8}$ of a wavelength long. The current distribution will then be substantially as indicated by the shaded portions 42a—46a and 42'b. It will be noted that in 44, 44'; 43, 45; and 43', 45'; the current distribution is equal so that at any point from the midpoints of these lines complete neutralization of vertical polarization may be achieved. The currents in the arms 44, and 43, 43', are not quite equal but are of the same order of magnitude and consequently substantial neutralization will occur at angles to the loop sides. A more complete explanation of this neutralization will be made later in connection with Fig. 10. This arrangement of antenna is particularly advantageous for use on portable receivers, since the antenna itself may be made very small still preserving a fair efficiency and a high degree of discrimination against waves not polarized in the plane of the antenna.

In Fig. 2 is illustrated an antenna 50 in accordance with a practical structural arrangement of the antenna shown in Fig. 1. In this arrangement leads 56, 56' are bent downwardly and are enclosed in a grounded shield 57, and the feeders 52, 52', are also enclosed in a grounded shield 58. This construction prevents radiation from these portions of the system so that no vertically polarized waves will result therefrom. Because of the parallel capacity effect of the shield, conductors 56, 56' are considerably shorter in physical length to obtain the devised electrical length, than if no shielding is present.

In Fig. 3 is shown a modification of the arrangement illustrated in Figs. 1 and 2 utilizing a single leg of the loop, the other leg being con-

stituted by the image conductors in the conductive surface. In this arrangement a high frequency source 61 is coupled over a shielded conductor 62 to the radiating loop 63, the end of the conductor being constituted by shielded open ended conductor 64. The dimensions of the single conductor of this modified loop are preferably made the same as those illustrated in connection with a single conductor of Fig. 1. As a consequence the radiation pattern of the antenna of Fig. 3 is substantially similar to that produced by the structure illustrated in Figs. 1 and 2.

In Fig. 4 is illustrated a further embodiment of my invention utilizing four different radiating conductors instead of two as in the other embodiment. This structure is especially adapted for use as a radiating antenna, since with the four conductors a larger radiation resistance and a consequent increase in energy radiation may be obtained. It is clear, however, that this antenna may also be utilized for reception, since it also provides an increased amount of pick-up.

In Fig. 4 is provided a high frequency source 70 coupled over conductors 71, 72 to four radiators 73, 74, 75 and 76. High frequency source 70 is preferably connected to the mid-point of conductors 71, 72 and the electrical length from the point of connection to the radiating conductors 73, 76 and to the ends thereof as shown at 73', 76' is made electrically equal to an integral half-wave length of the operating frequency. Conductors 73, 74, 75 and 76 are arranged in a square and the end of each radiator is bent inwardly as shown at 73', 74', 75', 76', so that only the central portions of the conductors are utilized for radiation. Radiators 73 and 76 are fed directly from high frequency source over conductors 71, 72, and radiators 74, 75 are fed over conductors 72, 71 to a means for producing a 180° phase shift such as the transposition shown at 71. As a consequence the currents flow through the conductors in the direction indicated by the arrows, the current disposition in each of the four radiators is uniform, as indicated by the solid shaded area 73a to 76a. Each radiating section is preferably made short with respect to the operating wave length so that the current distribution is high throughout the length thereof, and since the current distribution is equal in each of the four arms, and is opposite in phase on the opposite sides thereof, the vertical field component will be substantially eliminated in every direction and for every vertical angle with respect to this radiator. Furthermore, since substantially uniform current distribution is provided in the radiator the resulting radiation pattern will be substantially circular.

An embodiment of the antenna in accordance with the principles set forth in connection with Fig. 4, is illustrated in Figs. 5 and 6. In this arrangement the radiators consist of four members 801, 802, 803 and 804. These members may be comprised of hollow tubular conductor if desired to decrease the weight. Each of these radiators extends through entrance type insulators 805 into metallic shielding boxes designated as 806. Tubular metallic shielding members 807 extend downwardly and inwardly to metallic shielding box 808 from the lower end of which extends the shield 809. The energy feeding leads of the antenna 810 extend downwardly from diagonal corners of the antenna to the metallic tube 807 into the shielding box 808 where the transposition is made and any necessary impedance matching of

the antenna to the feed supply leads 813, is made. The other or reentrant end of the radiators 801, 802 extend downwardly in the opposite diagonally arranged shielding tube 807 and so are completely shielded. With this arrangement only the parts of the whole radiating structure containing the current loops are exposed to the weather. The insulators 805 at the end of the radiators are near voltage nodes of the system, so that no high voltage strength existed thereacross. The entire supporting frame is arranged beneath the radiating structure and inside the patterns thereof so that no part of the supporting frame is in the field of the radiators. The radiation resistance of this structure is high in comparison with the resistance of the wires or insulators so that a very high efficiency is obtained.

In an actual demonstration of an arrangement in accordance with this construction, it was found that the radiation pattern was substantially circular in the horizontal plane.

The radiator of the system according to my invention may be of shape other than straight conductors. In Fig. 7 is illustrated an arrangement similar to that shown in Figs. 5 and 6, except that the radiators are each curved so as to form substantially a circular pattern when assembled. Similar reference characters are used in Fig. 7 to designate the various elements corresponding to those shown in Figs. 5 and 6.

The radiating system may be composed of more than four conductors, for example, it may comprise eight units arranged in the form illustrated in Fig. 8. In this figure the high frequency load or source 1100 is coupled to a pair of transposed conductors 1101. These conductors are connected to radiators 1102, 1103, 1104 and 1105. Other radiating conductors 1107, 1108, 1109 and 1110 are arranged as shown in Fig. 8. In each of these conductors the terminating ends are bent inwardly as shown and arranged close thereto. This arrangement of the terminating ends of these radiators provides a coupling between the directly energized antennae elements 1102, 1103, 1104 and 1105, so that each of the other sections 1107 to 1110, inclusive, are also energized. Thus is provided a radiating antenna for radiating only horizontally or other plane polarized waves into which a high radiation resistance may be obtained and consequently a greater efficiency of operation.

Instead of using the inturned ends of conductors for coupling together the sections as shown in Fig. 8, condensers may be used as shown at 1100', Fig. 8A. In this case it may be more convenient to make the condensers in the form of strain insulators and the radiant acting sections may be bent in their centers for fastening to a support.

In Fig. 9 is illustrated a vertical section to the radiation pattern produced by antennae in accordance with my invention. The horizontal axis is designated by HH and the vertical axis by VV. The field is represented by the tangent curves F, F'. The field is actually in the form of a lemniscate similar in pattern to that obtained from the radiation of a single dipole, but differs therefrom in that there are no vertically polarized components. The voltage at any point in the field may be expressed by equation $E = E_0 \cos \theta$ where E_0 is the voltage in the horizontal frame and θ indicates the angle of elevation.

The radiation resistance for antennae in accordance with my invention wherein the current

distribution throughout the arms is substantially uniform may be expressed by the equation

$$R = 320 \left(\frac{\pi \sqrt{A}}{\lambda} \right)^4 \text{ ohms}$$

where R is the radiation resistance, A is the area of the loop in given units and λ is the working wavelength in the same type of units as area A . For the square loop arrangement such as shown in Figs. 4, 5 and 6, the radiation resistance

$$R = 320 \left(\frac{\pi l}{4} \right) \text{ ohms}$$

where l is the length of one of the radiators in the same units as the wavelength λ . A preferred range of radiation resistance is between 7 and 20 ohms.

A more complete explanation of the operation of the antenna in accordance with the principles of my invention may be obtained by reference to Fig. 10, showing a three dimensional view of a quadrant of the radiation field from a radiator similar to that illustrated in Fig. 4. The arms corresponding to the four radiators of the antenna are designated by letters A, B, C and D, as shown, with arms A and C being opposite each other and arms B and D being arranged opposite to each other. The intersection of the planes are designated by the heavy lines X, Y and Z, the horizontal plane being the X, Y plane, the two vertical planes being the Z, Y and Z, X planes, these planes being bounded by curves XY, ZY and ZX, respectively. A third plane is passed through the diagonal of the radiator represented by the lines Z and W, and bounded by the curve w. At any point P on the line w, making a vertical angle with the plane of the radiator, can be assumed to be a receiving point. The dot-dash line starting at X and extending through point P, represents the meridian of polarization of energy from radiators A and C, and the broken line extending from Y through point P, represents the meridian of polarization from radiators B and D. At point P the radiation from radiator C will have a large horizontal component and a small vertical component as shown at c, and at the same time the radiator D will produce a horizontal component in the same direction as that from C and a small equal vertical component oppositely phased to that of point C. It is therefore clear that these two vertical components being equal and opposite will cancel, since P is equi-distant from both radiators B and D. Similarly at point P the vertical components from radiators A and B will cancel as shown at a, b, and the horizontally polarized components will add together in phase although they are of opposite phase from elements C and D. Since radiators A and B are at different distances from point P than radiators C and D, there will be a horizontally polarized component which can be received. The vertically polarized components, however, are completely cancelled as explained.

At points P_1 still at the same vertical angle it can be seen that the radiation from elements from radiators B and D, will be largely vertical but will be in opposite directions. Since point P_1 is equi-distant from radiators B, D, the vertically polarized waves will therefore be cancelled at this point. The horizontally polarized waves at point P_1 , arriving from radiators A and C, are of opposite phase but since they come from different distances, a horizontal component

will be present for reception. Similarly at point P_2 the horizontally polarized component from B and D will be received, whereas the vertically polarized component from A and C will be neutralized. If the vertical angle at which P is located is varied, the same effect will occur, since as shown, P represents a point at any vertical angle. Similarly, since the points chosen for illustration represent the extremes in so far as the radiator is concerned, it is clear that the vertically polarized components will be neutralized everywhere about the loop regardless of the horizontal angle.

In planes intermediate the 90 and 45 degree position discussed in detail above, for example, in a plane nearer the X axis, the vertically polarized components from B and D increase but will approach equality in opposite phases. The vertically polarized components from A and C will also approach equality in opposite phase. As a result the sum of the vertically polarized components at this intermediate point will be such that the components from A plus the components from D is equal in magnitude but opposite in phase to the vertically polarized components from B plus the corresponding component from C. Accordingly, it is seen that the vertically polarized components will neutralize in every direction about the antenna. Careful test measurements of vertical components about such an antenna verify this conclusion.

This explanation has been made with reference to the four armed loop such as shown in Fig. 4. It is clear that the same principles apply in varying degrees to the other arrangements such as those shown in Figs. 1, etc.

In the arrangements as shown in Fig. 1 the neutralization, however, will not be as complete in all directions because there is not a complete equality of currents in the loop sections. For example, turning to Fig. 1, it is clear that the current in 44', for example, is not exactly equal to the sum of the currents in 45 and 45' and for this reason a complete neutralization of the vertical components will not be present. However, a close approximation of complete compensation may be achieved by use of this loop.

In Fig. 11 is illustrated an installation of a loop according to my invention, for use as a receiver. This loop is designed for receiving two different frequencies and for this reason is somewhat of a compromise in design. In this installation the two radiators 1301 and 1302 were arranged to form an oval loop approximately 17" long and 10" on the minor axis. The two frequencies f_1 , f_2 for which the circuit was designed, are 93 and 109 megacycles, respectively. The receivers are represented at 1303, 1304 in the drawing. A metal plate 1305 mounted on an insulating handle 1306 is provided for vernier tuning of the circuit. The radiators are coupled over a special loaded line 1307 across two shielded conductors 1308, 1309. Section 1308 is made equal to one-half of the wavelength λ_2 , for which receiver 1304 is designed. Thus the line is rendered tuned to f_2 so that any addition at the termination of line 1307 will not affect the line substantially for energy of f_2 . 1304 is inductively coupled to line 1308 by a tuned coupling so that energy other than that for which it is designed will not be received. Receiver 1303 tuned to f_1 is coupled over a shielded pair symmetrically to the antenna over 1308 and 1307. The metal shields around line sections 1308, 1309 are conductively joined together. The

line 1307 is made by means of a special loading approximately a quarter of a wavelength long electrically although the actual length is much shorter. In the installation the actual length of line 1307 was approximately 11". A concentric line 1310 is used to connect transmission line section 1308 to receiver 1304, and a shielded pair transmission line 1311 is used to couple section 1309 to receiver 1303. In the installation actually made the shields about line sections 1309, 1308 were made of concentric tubular conductors of $\frac{3}{8}$ " outer diameter and the concentric transmission sections 1310, 1311 were made of concentric transmission lines of one-quarter inch outer diameter.

The loaded line 1307 has a relatively high value of surge impedance. This extra high value of surge impedance was found desirable in order to reduce the circulating current in the half-wave length line. The impedance of the loop itself at the upper terminals may be very high, for example, say the value is R . Then the impedance at the bottom of the special section line 1307 is

$$r = \frac{Z_0^2}{R}$$

where Z_0 is the surge impedance of the line. When Z_0 has a low value, impedance r is very low and consequently there is a large current flowing into the half-wave length line. This large current produces losses in the conductor shield. Actual tests have shown that when special loaded line 1307 was replaced by an open air line consisting of two copper rods a quarter inch in diameter and spaced three-quarters of an inch apart, the total loss at 109 megacycles was about four decibels. With the loaded line which was made of number 14 tinned wire and loaded with four coils of about twelve turns each, with an outer diameter of about a quarter of an inch, spaced a half an inch apart the total loss was reduced to one decibel. In order to complete the shielding, screening boxes 1314, 1315, may be provided.

A further modification by way of improvement of the antenna shown in Fig. 11 is illustrated in Fig. 12. In the loop installation such as shown in Fig. 11, a considerable voltage exists in the loop at the ends of the loop where it is supported by its insulators. The consequent high impedance at the insulators leads to two troubles. (1) The tuning of the loop is relatively sensitive to additions of capacity, for example, snow may produce a 10% effect, and (2) the high impedance of the insulator requires the use of such a loaded line to reduce loss in the two frequency, tuning circuit illustrated.

Even with the specially loaded line it may still be necessary to use fairly large concentric tubing for the half-wave line section to reduce losses to a reasonable value. The use of a lighter concentric line, for instance, a quarter-inch line would be preferable because of the ease in bending and lighter weight.

In order to improve the operational characteristics in so far as this voltage distribution is concerned, the loops may be constructed in accordance with the showing of Fig. 12. In this arrangement each of the arms 1401, 1402, are broken up by means of condensers 1403. The voltage distribution about the loop becomes about in the form represented at V. At the same time the current distribution in these parts of the conductors is approximately as represented at

10 I₀ in the lower half of Fig. 12. Considering the surge impedance of the loop conductors as Z_0 , and the distance between two consecutive condensers as 2θ , then $V = Z_0\theta \sin \theta I_0$. Where I_0 is the low loop current which occurs half-way between the condensers; the general current $i = I_0 \cos \theta$; the capacity C of a condenser is determined from the following formula

$$1/C = 2Z_0 \tan \theta$$

where

$$\omega = 2\pi \times \text{frequency}$$

For example when

$$F = 100 \text{ m. c.}$$

$$Z_0 = 500 \text{ ohms}$$

$$\theta = 10"$$

that is 2θ about 6", then

$$20 C = \frac{10^{12}}{6.28 \times 10^8 \times 10^3 \times .176} = 9 \mu\mu F$$

It is seen that the capacity C of condenser 1403 is very small. This capacity may be obtained by a very simple fitting such as illustrated in Fig. 13. In this arrangement the conductor forming the radiators 1501, 1502, may be a metal tube, for example, aluminum tubing. Into the ends of these tubes is inserted an insulator 1503, which may be a ceramic tube. Through the tube is inserted a metallic rod 1504 provided with enlarged ends 1505, 1506, which will serve as the seats of capacity for the condenser. Tube 1504 may also be of aluminum. The two conductors 1501, 1502 are then clamped in position on insulator 1503, by means of clamping rings 1506, 1507.

25 By replacing the loop shown in Fig. 11 by a loop provided with condensers such as shown in Figs. 12 and 13, the voltage at the insulators would be reduced to about one-third of the value without the condensers and the impedance would be reduced to about one-ninth of the value obtained otherwise. It is clear that with this type of loop, the circuit will be much less sensitive to capacity changes such as caused by snow or ice, and furthermore the loss in tuning the circuit will be considerably reduced.

30 35 Because of the substantially complete absence of vertically polarized components the antennae in accordance with my invention are particularly suitable for use as horizontally polarized guiding beacons or runway localizer beacons, since they will not produce faulty shifting of courses due to variations in polarization at vertical angles. One form of radio beacon arrangement utilizing antennae in accordance with my invention is illustrated in connection with Figs. 14 to 16.

40 45 In Fig. 14 two antennae 1601 and 1602 are shown, preferably mounted a half a wavelength of the operating frequency apart. These antennae are preferably of the type illustrated in Figs. 5 and 6, but may be of any of the other types illustrated in the application. Antennae 1601 and 1602 are connected together over a transmission line 1603. Coupled to the transmission line 50 55 60 65 70 75 1603 is high frequency apparatus 1604 connected by means of line section 1605 midway between antennae 1601 and 1602. A 180° phase shift is provided, for example by a transposition provided in line 1603 at 1606. Thus antennae 1601, 1602 are located a half-wavelength apart and are energized in phase opposition. This energization of the loops in phase opposition produces a radiation pattern having a null point midway between the two antennae, as shown in Fig. 16 at F1. If the transposition 1606 is omitted, then antennae 1601,

1602 will be energized in phase. This will produce a radiation pattern having a null in the direction of the extension of the antennae, as illustrated at F₂, in Fig. 16. These variations in radiation pattern may be produced by any suitable keying means for alternately transposing the line.

In Fig. 15 is illustrated an arrangement for producing a guiding course by simultaneous energization of two antennae spaced a half-wavelength apart. The antennae 1701, 1702 are connected over transmission lines 1703, 1704', to opposite corners of a balanced network indicated generally at 1704. This network is preferably made of open lines and is provided with two sets of arms 1705, 1706, a transposition is arranged in arms 1705. Because of this transposition energy introduced or withdrawn at any corner of the network will have no effect on the apparatus connected diagonally opposite therefrom as long as the impedances are balanced, although it may effect any apparatus connected to the other corners. A transmitter which may be a common high frequency source 1710 is provided, from which is derived two separate signalling energies which may be differently modulated with frequencies F₁, F₂. The energy thus modulated is transmitted from the separate transmitter output 1711, 1712. Energy from 1711 modulated at F₁ is applied to one corner of the bridge 1704, so that radiators 1701, 1702, are energized over the transposed section and thus radiate the pattern F₁ of Fig. 16.

Simultaneously the energy from 1712 is applied to the diagonally opposite corner of the network 1704 so as to feed antennae 1701, 1702 in phase. Thus there results a pattern such as shown at F₂ of Fig. 16.

The four arms of bridge 1704 are preferably in length equal so that at point b looking in from a, the effect is the same as though a short circuit existed at this point. However, arms 1705, 1708, and 1706, 1707 may not present an impedance match with respect to energy entering from point a, and reflections from b, will result. Similarly energy from point b will be reflected at a. By properly dimensioning the arms the lengths may be so chosen that the reflected energy will just compensate for the mismatch and the circuit will operate so as to prevent reflections on the feeding lines. I have discovered that in order to provide for this effect the individual arms of the bridge network should be substantially .15 of a wavelength long at the operating frequency.

As shown in Fig. 16 the radiation patterns are not circular but are deformed so that pattern F₁ is somewhat flattened and F₂ is elongated. The courses are consequently at an angle less than 90° as in the case of circular radiation patterns. The courses actually extend at about 60° with respect to one another. There is provided a beacon arrangement for forming four separate guiding lines towards the beacon. Since the antennae units also are provided to cause substantial neutralization of the vertical field component, the beacon signals will be derived solely from horizontally polarized waves. Thus any receiver coupled to this system will operate to give the proper course, regardless of any variation in the polarization of the receiving antennae.

In Fig. 17 is illustrated another form of beacon particularly useful for the utilizing antennae in accordance with the principles outlined above. In this figure high frequency source 1710 is coupled to two modulators 1711 and 1712 and to a bridge network 1704, similarly to the arrange-

ment illustrated in Fig. 15. The arms of the bridge network are preferably made .15 of a wavelength long as explained in connection with Fig. 15. However, instead of only two antennae, four antenna units 1721 and 1724 are provided. Units 1721 and 1724 are connected together by a transmission line 1725 in which is provided the phase reversal means, such as the transposition 1723, so that they are energized in phase opposition. Line 1725 is connected to one corner of bridge 1704 by line 1727, at a point electrically midway between 1721 and 1724. Two other antennae 1722, 1723 are connected together by a transmission line 1728 which is connected by means of a line 1729 to the corner of bridge 1704 diagonally opposite the point of connection of 1727. Line 1729 is made 90° shorter electrically than 1727 so that these units are energized in phase quadrature with respect to units 1721 and 1724.

The energy supplied from modulator 1711 modulated at frequency f₁ then energizes antennae 1721, 1724 at 180° phase difference, as indicated in the drawing, and simultaneously energizes antenna 1722, 1723, in phase with energy at -90° phase displacement with respect to energy supplied to the other two antennae. Similarly, energy from 1712 modulated at f₂ energizes antennae 1721, 1724 at 180° phase difference but also at 180° out of phase with energy from 1711. The antennae 1721, 1724 are displaced a distance α from the center line of the array and antennae 1722, 1723 are spaced apart a distance β . The radiation pattern from these arrays will then be formed somewhat as shown in Fig. 18. In this figure the broken line curve F'₁ represents the transmission pattern from modulator 1711, and the solid line curve F'₂ represents the energy transmitted from 1712. The modulator 1711 may be provided to furnish a modulation frequency, for example, 170 cycles, and modulator 1712 a modulation of different frequency, for example, 90 cycles, so that the signal equality course may be readily determined on a craft. Both patterns F'₁, F'₂ have some minor lobes of radiation but these are of such small amplitude as to be neglected with respect to the main guiding part.

The spacing between the antennae may be varied to change the shape of the radiation pattern. However, a preferred form using a spacing in which α equals 170 electrical degrees, and β is made equal to 160 electrical degrees, produces a very sharp pattern free from bothersome minor lobes of radiation.

For use as radio beacons, the structure shown in Figs. 5 and 6, presents some difficulties since the shielding arrangements such as 807, are at an angle to the vertical and are also disposed in the radiation field of the other antenna unit. For this reason these angularly disposed sections will pick-up and reradiate some energy and for this reason interfere with the pure horizontal polarization. In order to overcome this difficulty the antennae may be constructed in the manner shown in Figs. 19 and 20 so that substantially no vertically polarized radiation will be produced.

In Fig. 19 a front view of this antenna is shown with the cover of central boxes removed so as to show the construction. According to this arrangement, two hollow metal boxes 1901, 1902 are provided. To the other side of each of these boxes is fastened a concentric cable arrangement 1903, 1904, the center conductor

of which may be used to feed the antennae. In the sides of boxes 1901, 1902, at the point where they are adjacent each other, a hole is provided so that a transposition of the feeding conductors may be achieved. These conductors 1905, 1906 are led through suitable shields to the radiant acting conductors 1911 to 1914, inclusive. Conductors 1911 to 1914 are preferably made heavy and may be as shown, made of strips of metal, such as copper. By making these elements of large dimensions, the resistance thereof is greatly decreased. This is of importance since by decreasing the surge impedance of the radiators themselves, considerable reduction of the voltage across the insulators connecting conductors 1906, 1905, may be achieved. The in-turned end of the conductors 1911 to 1914, are supported by means of a plate 1917 and may be covered by suitable weatherproof covering 1918. By this arrangement all of the angularly related conductor portions are obviated, and consequently harmful vertically polarized radiations are averted.

It should be noted that the beacon arrangements disclosed herein are well suited for producing radiation beacon patterns. It is further noted that the spacing between the antennae units is such that radiators of a half wavelength could not be used. Therefore, the particular antennae units in accordance with my invention are admirably suited for this purpose. It should be understood, however, that the particular balancing arrangement and the beacon system may be utilized also, with other forms of antennae, than those producing horizontal polarization.

While I have illustrated a few preferred embodiments of my invention, it should be distinctly understood that this description is made merely by way of illustration and is not intended as a limitation on the scope of my invention. What I intend to cover as my invention is defined in the accompanying claims.

What I claim is:

1. A radio beacon system for operating at a given frequency comprising a pair of spaced radiating means, a first energy source for producing waves of said operating frequency characterized by a particular signal, a second source of energy for producing waves of said operating frequency characterized by a second signal and means for supplying energy from said first source to said radiating means in one phase relation, and from said second source in a different phase relation, comprising a two conductor four arm reentrant bridge network having a 180° phase shifting means in one arm thereof, coupling means coupling diagonal junction points of said arms to said radiating means, means coupling said first source of energy to said bridge at the junction point of said arm provided with said phase shifting means and a second arm other than the radiating means coupling points, and means coupling said second energy source to said bridge at the junction point of said arms diagonally related to said last named junction, the arms of said bridge each being of substantially equal lengths, and so dimensioned with respect to the wavelength at said operating frequency as to produce reflections of energy from one source of such magnitude as to compensate for impedance mismatch of the system with respect to the energy coupling means of said source.

2. A radio beacon system according to claim 1,

wherein said radiating means comprising antennae units designed to transmit only horizontally polarized waves.

3. A radio beacon system according to claim 1, wherein each said radiating means comprise an antenna including a plurality of horizontal conductors arranged to outline a substantially closed periphery for radiating only horizontally polarized waves, said means being spaced apart substantially one-half a wave length at said operating frequency.

4. A radio beacon system according to claim 1, wherein each said radiating means comprises a group of at least two antennae, each including a plurality of horizontal conductors arranged to outline a substantially closed periphery, for radiating only horizontally polarized waves, the antennae of one of said groups being spaced apart a distance less than one-half a wave length at the operating frequency, and being arranged centrally with respect to the antennae of the other group.

5. A radio beacon system for operation at a given frequency comprising a pair of spaced radiating means, a first energy source for producing waves of said operating frequency characterized by a particular signal, a second source of energy for producing waves of said operating frequency characterized by a second signal and means for supplying energy from said first source to said radiating means in one phase relation, and from said second source in a different phase relation, comprising a two conductor four arm reentrant bridge network having a 180° phase shifting means in one arm thereof, the arms of said bridge each being .15 of a wavelength long at said given frequency, coupling means coupling diagonal junction points of said arms to said radiating means, means coupling said first source of energy to said bridge at the junction point of said arm provided with said phase shifting means and a second arm other than the radiating means coupling points, and means coupling said second energy source to said bridge at the junction point of said arms diagonally related to said last named junction.

6. A radio beacon system comprising a pair of antennae each designed to transmit substantially only horizontally polarized waves and spaced less than a half wavelength apart at the operating frequency, means for energizing said antennae in phase coincidence with energy of said operating frequency characterized by a particular signal and means for energizing said antennae in phase opposition with energy of said operating frequency characterized by a different signal, whereby four guiding courses are provided consisting only of horizontally polarized energy waves.

7. A radio beacon comprising a first pair of antennae designed to transmit substantially only horizontally polarized waves and spaced apart a distance less than one-half wavelength at the operating frequency, a second pair of antennae designed to transmit substantially only horizontally polarized energy and spaced substantially equal distances on either side of said first pair of antennae, means for supplying energy characterized by a distinct signal to the antennae of said second pair of antennae in phase opposition, and to the antennae of said first pair in like phase and in phase quadrature with respect to said second group antennae, and means for supplying energy characterized by a different signal to said antennae of said first and second pair in

phase opposition to said first supplied energy, whereby a two guiding course consisting of only horizontally polarized energy is provided.

8. In a high frequency system, a first source of energy of a given frequency, a second source of energy of said given frequency, two load circuits for said energy, and means for feeding energy from each of said sources to said loads in different phase relation, comprising a closed bridge network comprising four serially connected arms of substantially equal length, means in one of said arms for producing a 180° phase shift, means for coupling said first and second

energy sources to diagonally opposed corners of said bridge network, and means for coupling said loads to the other diagonally related corners of said bridge, the arms of said bridge being so dimensioned as to produce a reflection of energy from said source just sufficient to neutralize the effect of the inherent mismatch of said network to said energy coupling means.

5 9. A high frequency system according to claim 8, wherein said arms of said bridge are substantially .15 of a wavelength long at said given frequency.

10 ANDREW ALFORD.
